DESIGN FOR A CHAIN GUARD FOR A BICYCLE

John R. Morgan, Oak Park, Ill., assignor to
Sears, Roebuck and Co., Chicago, Ill., a corpo-
ration of New York

Application November 23, 1938, Serial No. 81,301

Term of patent 7 years

To all whom it may concern:

Be it known that I, John R. Morgan, a citizen
of the Republic of Guatemala, residing at Oak
Park, in the county of Cook and State of Illi-
nois, have invented a new, original, and orna-
mental Design for a Chain Guard for a Bicycle,
of which the following is a specification, refer-
ence being had to the accompanying drawing,
forming a part thereof.

Fig. 1 is a top plan view of a chain guard for
a bicycle embodying my new design.

Figs. 2 and 3 are side elevational views of the
same, showing respectively the two sides thereof.

Figs. 4 and 5 are sectional views taken sub-
stantially along the lines 4—4 and 5—5 of Fig. 2.

I claim:

The ornamental design for a chain guard for
a bicycle, as shown.

JOHN R. MORGAN.
